UNITED STATES PATENT OFFICE.

RALPH E. REID, OF BROOKLYN, NEW YORK.

PUZZLE.

Specification of Letters Patent. Patented Aug. 6, 1918.

1,274,593.

Application filed August 13, 1917. Serial No. 185,994.

To all whom it may concern:

Be it known that I, RALPH E. REID, a citizen of the United States, residing at Brooklyn, in the county of Kings, State of New York, have invented certain new and useful Improvements in Puzzles; and I do hereby declare the following to be a full, clear, and exact description of the invention, such as will enable others skilled in the art 10 to which it appertains to make and use the same.

This invention relates to puzzles and has for its object to provide a puzzle which, in its solution, will require the accomplishment 15 of two feats, each reasonably difficult in itself.

Another object is to provide a puzzle susceptible of two solutions, one being more difficult than the other so that the puzzle 20 may be used as a novel and interesting game, as will be understood from the following.

In the drawings:—

Figure 1 is a top plan of the present 25 puzzle.

Fig. 2 is a section on line 2—2 of Fig. 1, with the fugitive ball in the central depression and the pursuing ball in position for engagement thereover in the final operation of solving the puzzle.

Fig. 3 is an enlarged detailed sectional view showing the pursuing ball in engagement over the fugitive ball in the position which it occupies when the puzzle is solved.

Fig. 4 is a top plan of a modified form of the invention.

Fig. 5 is a detail section showing the arrangement of the obstacle pins.

Referring now to the drawings, the present 40 invention comprises a circular board 5 having a circumscribing upstanding wall 6 to the upper edge of which there is secured a circular transparent cover 7.

Formed in the upper surface of the board 45 5 there is a semi-spherical depression 8, and formed also in the upper surface of the board 5 in a circular series surrounding the depression 8, there are four similar depressions 9 which are spaced ninety degrees 50 from each other. Between each of the depressions 9 and the depression 8 the board 5 carries an upstanding wall section 10, these several wall sections being curved longitudinally upon an arc concentric with 55 the center of the board, and the several sections are equi-distant from the center of

the board so that they are disposed in a circle. The several sections are spaced from each other at their ends so that in effect there is produced a circular upstanding 60 wall surrounding the central depression 8 concentrically and provided with four passages 11 therethrough. As will be seen in Fig. 1, these passages 11 are located half-way between the adjacent depressions 9. 65

Employed in connection with the above described board there are two balls, a small ball which is known as the fugitive ball, indicated at 12, and which is of a size to seat itself within the depressions 8 and 9, and a 70 large ball, known as the pursuing ball, indicated at 13. The ball 13 has formed in its surface a semi-spherical depression 14 which is of a size to receive the ball 12 therewithin.

The object of the present puzzle is first to 75 bring the ball 12 into one of the depressions 8 and 9 by manipulating the board and then, by further manipulation of the board, to bring the ball 13 into such a position that its recess 14 will be engaged over the ball 12 80 while that ball is still within the depression into which it has been brought. It is obvious that this operation may be performed more easily if one of the depressions 9 be selected, than if the depression 8 be selected, 85 since the wall sections 10 interrupt the free movement of the ball 13 making it necessary for this ball to pass through one of the passages 11 in order to reach the central depression 8. Thus the puzzle is capable of 90 two solutions, a solution involving any one of the depressions 9 being less difficult than the solution involving the depression 8.

The present puzzle may be used as a game 95 played by two or more individuals, the board being passed from one to another, and the score of each player being determined by the solution which he brings about, a solution involving the depression 8 counting perhaps twice as much as a solution involving 100 any one of the depressions 9.

In the drawings I have illustrated the board as marked with an inscription calculated to lend interest to the solution of the puzzle, and I have illustrated the fugitive 105 ball as bearing the likeness of a human face, while the pursuing ball is illustrated as bearing the words "Uncle Sam."

It will be understood, however, that I 110 do not wish to be limited to the special inscription appearing upon the board or the particular decoration of the balls.

It is to be noted especially that, by reason of the fact that the depression 14 is formed in the surface of the ball 13, the remainder of the ball being solid, the tendency will be 5 for the ball 13 to come to rest with the recess 14 uppermost and thus the manipulation of the board must be done with the utmost care to insure the centering of the recess 14 upon the ball 12. In Fig. 2 I have illustrated the balls in a position just prior to 10 the final solution of the puzzle. If the two balls are disposed as illustrated in this figure, and the board then properly tilted, the ball 13 will be moved in such a way as to 15 receive the ball 12 into the recess 14.

In Figs. 4 and 5 there is shown a modified form of the invention in which the wall sections 10 are eliminated and in which the board 5 is provided with a plurality of 20 up-standing obstacle pins, indicated at X, one of these pins being located between the depression 8 and each of the depressions 9, others of the pins being located between the 25 depressions 9. It will of course be understood that these pins interrupt the free movement of the ball 13 over the surface of the board.

What is claimed is:

1. A device of the class described comprising 30 a base portion having a semi-spherical depression therein, an upstanding wall carried by the base portion and surrounding the depression, said base portion having formed 35 therein a circular series of semi-spherical depressions surrounding the first depression

concentrically thereto, an upstanding wall carried by the base portion between the first mentioned depression and the surrounding series of depressions, said wall having a passage formed therethrough, a ball disposed 40 within the inclosure of the first mentioned wall, said ball being of a size to seat in any one of the depressions and to extend therefrom above the upper surface of the base, and a second ball located within the 45 inclosure of the first mentioned wall and having a semi-spherical recess in its surface of a size to receive the first mentioned ball snugly therein.

2. A device of the class described comprising 50 a base member having a semi-spherical depression therein, an upstanding wall carried by the base member and surrounding the depression, a ball disposed within the inclosure of the wall, said ball being of a size 55 to seat within the depression and to extend above the upper surface of the base portion, a second ball disposed within the inclosure of the wall and having a semi-spherical recess in its surface of a size to receive the 60 first mentioned ball therein, and spaced up-standing elements carried by the base member within the inclosure of the wall.

In testimony whereof, I affix my signature in the presence of two witnesses.

RALPH E. REID.
